LAWN SPRINKLER

William P. O'Brien, Western Springs, Ill., assignor to
W. D. Allen Manufacturing Co., Chicago, Ill., a corporation of Illinois

Application May 29, 1958, Serial No. 51,122

Term of patent 14 years

(Cl. D91—1)

Fig. 1 is a perspective view of a lawn sprinkler, embodying the new design;

Fig. 2 is a top plan view of the same;

Fig. 3 is a front elevational view of the same;

Fig. 4 is a side elevational view of the same; and

Fig. 5 is a bottom plan view of the same.

The sprinkler head is omitted in Figs. 2-5 inclusive for convenience of illustration.

The dominant features of the design reside in the portions shown in full lines.

I claim:

The ornamental design for a lawn sprinkler, as shown and described.
